UNITED STATES PATENT OFFICE.

JAMES R. MCCELLIGOTT, OF CHICAGO, ILLINOIS.

FIRE-DOOR CASING FOR FURNACES.

SPECIFICATION forming part of Letters Patent No. 325,105, dated August 25, 1885.

Application filed June 6, 1885. (No model.)

To all whom it may concern:

Be it known that I, JAMES R. MCCELLIGOTT, a citizen of the United States, and a resident of the city of Chicago, in the county 5 of Cook and State of Illinois, have invented certain new and useful Improvements in Fire-Door Casings for Boilers, Furnaces, and the Like, of which the following, when taken in connection with the drawings accompanying 10 the same and forming a part hereof, is a full and complete specification.

The object of my invention is mainly to secure a casing for the fire-doors of boilers and furnaces which will not burn or be burned 15 out when an intense heat is attained in the fire-box of the boiler or furnace, and also to provide means whereby heated air or air and steam may be supplied the fire-box above the surface of the fire therein.

20 I have illustrated my invention as applied to an ordinary boiler.

Figure 1 is a sectional view on line 1 1 of Fig. 2. Fig. 2 is a sectional view on line 2 2 of Fig. 1. Fig. 3 is a perspective view of one 25 of the sides of my improved casing, with a portion of one face broken away to show the interior thereof. Fig. 4 is a perspective view of the bottom plate of my improved fire-door casing, with a portion of the same broken 30 away, showing the interior thereof. Fig. 5 is a plan view of pipes D and D'.

Like letters refer to like parts throughout the several views.

W is the grate of the fire-box. X is the 35 boiler. Y is the fire-door. A is the bottom plate of the casing. A' is the top plate. B B are the side plates. D is a pipe having branches D' D'. E E are lugs or projections on the inner surface of the top and bottom 40 plates. F is a hollow space, forming an air-chamber in the top and bottom plates. F' is a hollow space forming an air-chamber in the side plates. a a are holes drilled or cast in plates A A'. b b are holes drilled or cast in plates B B. e e are holes drilled or cast in 45 top plate, A'.

The several plates used by me and illustrated by the drawings are each formed of an outer and inner wall, thus securing an air-chamber therein, and are provided with holes, cast or drilled therein, by which air is admitted into the air-chamber formed in the

lower plate, and allowed to circulate freely therefrom throughout the whole casing. Plates B B and A' also contain holes b b 55 and e e, through which air is admitted into the fire-box. Steam from the boiler is forced through pipe D and branches D' D' and through holes e e.

The manner in which my improved casing 60 is constructed is as follows: Bottom plate, A, is placed over the ash-door, and set in brick or metal in such manner that air may enter through holes a a on the bottom face or wall of said plate and circulate freely in and around 65 the air-chamber formed between the outer and inner wall of said plate. Side plates, B B, are set on bottom plate, A, and over holes a a therein, pressing against lugs E E, and the brick facing ordinarily employed for the front 70 of the fire-box is laid against the outer face of the outer wall of said plate B. Top plate, A', is then laid upon the upper edges of side plate, B B, and one or more courses of brick may be laid upon said top plate, A'. I prefer to so 75 place plate A' that but one course of brick shall rest upon the same between it and boiler X.

The manner in which my improved fire-door casing operates is: Air is admitted into chamber F of lower plate, A, through holes a a in 80 the lower wall thereof, and circulates more or less freely through and around said chamber F, and from said chamber passes through holes a a in the upper wall of said lower plate, A, into and around air-chamber F' of side plates, 85 B B. From air-chamber F' the air passes through holes a a in lower wall of top plate, A', in and around air-chamber F in said top plate, and air in said chamber F also passes through holes b b in plate B directly into the 90 fire-box. Air in chamber F of upper plate, A', passes through holes e e in the side wall of said top plate directly into the fire-box. As the air contained in said air-chambers F' and F becomes heated, it passes into the fire-box through holes b b and holes e e, a constant current of air being induced thereby. 95 This action, being greatly accelerated by the draft of the fire-box and the current of air being thus supplied being at a high temperature, greatly assists in the perfect combustion of the gases in the fire-box. In order that the supply of air thus heated and admitted into the fire-box may be increased, if desired,

by forcing steam through holes *e e* in top plate, A', thus increasing to a still greater degree the incidental or minor object of my invention, it is necessary merely that pipe D, with branches D' D', be placed in air chamber F of top plate, A'. Pipe D is connected with the boiler X. Pipes D' D' are of smaller outside diameter than is the inside diameter of holes *e e*, and stop just in front of or project a very little way into said holes *e e*. If, now, steam be admitted to pipe D and branches D' from the boiler, a very strong blast of heated air and superheated steam or steam enters the fire-box through said holes *e e*.
15 I am aware that various methods have been provided for supplying air or air and steam to the fire-box of a boiler or furnace over the fire therein, and I do not therefore claim this, broadly, as my invention, the main object of 20 my invention being to secure a casing for fire-doors of boilers and furnaces which will not burn or be burned out; and

What I claim, and desire to secure by Letters Patent, is—
25 1. A casing for fire-doors in boilers and fur-

naces, consisting of a hollow plate, forming the bottom of said casing, in combination with hollow side plates and a hollow top plate, all said plates having holes permitting the admission and circulation of air in said casing, 30 said side and top plate also having holes into said fire-box, all substantially as described, and for the purpose set forth.

2. A casing for fire-doors in boilers and furnaces, consisting of hollow plate A, having 35 holes *a a* therein, side plates, B, having holes *b b* therein, and top plate, A', having holes *a a* and *e e* therein, all combined substantially as described, and for the purpose specified.

3. A casing for fire-doors in boilers and 40 furnaces, consisting of hollow plates A' and B B, having holes *a a*, *b b*, and *e e* therein, in combination with pipe D, having branches D' D', all substantially as described, and for the purpose specified.

JAMES R. McELLIGOTT.
